Specification for Design.

Patented Oct. 13, 1914.

Application filed July 30, 1914. Serial No. 854,190. Term of patent 14 years.

To all whom it may concern:

Be it known that I, ZED HETZEL COPP, a citizen of the United States, residing at 1910 North Seventh street, Philadelphia, county of Philadelphia, State of Pennsylvania, have invented a new, original, and ornamental Design for a Home-Flag, of which the following is a specification, reference being had to the accompanying drawing, forming part thereof.

The figure is a plan view of the flag illustrating my design.

The figure is, upper part thirteen stars, with alternating red and white stripes on either side; bottom white field with Roman cross in red; right field, red, and left field, blue.

I claim:

The ornamental design for a home flag as shown and described.

ZED HETZEL COPP.
